UNITED STATES PATENT OFFICE

SIMON E. SCHROEDER, OF NEWTON, IOWA, ASSIGNOR, BY MESNE ASSIGNMENTS, TO AUTOMATIC WASHER COMPANY, OF NEWTON, IOWA, A CORPORATION OF DELAWARE

METHOD OF FORMING WASHING-MACHINE DOLLYES

Application filed September 22, 1927. Serial No. 221,154.

This invention relates to dollies for washing machines.

One of the objects of the invention is in the provision of an all-metal dolly for washing machines.

Another object is in the provision of a stamped metal dolly for washing machines, which is simple in construction and considerably lower priced than the dollies composed of different materials or constructed in other manners.

Still another object lies in the method of forming a washing-machine dolly by using metal stampings and combining them in such manner that there is produced a simple and sturdy washing-machine agitator.

Other objects will appear in the following specification taken in connection with the annexed drawings, in which—

20 Fig. 1 is a plan view of the dolly;

Fig. 2 is a sectional view taken on the line 2—2 of Fig. 1;

Fig. 3 is a sectional view taken on the line 3—3 of Fig. 1;

Fig. 4 is a sectional view taken on the line 4—4 of Fig. 1;

Fig. 5 is an end elevation of one of the agitator blades; and

Fig. 6 is a side elevation showing in detail one of the agitator blades.

The present applicant has watched the development of washing machines, and especially the so-called dolly type, from the original machine which utilized either the so-called peg type of dolly or at least some sort of paddle arrangement for agitating the clothes in the water, as well as several other types of dolly of more recent construction.

40 The other well-known types of dolly with which applicant is familiar are namely those constructed either of wood, with wooden blades thereon, those constructed of cast or die-cast aluminum, and those formed either of a phenolic condensation product or rubber.

45 As a matter of fact, the present applicant was the originator of the flexible rubber dolly and was granted a patent thereon.

The above types of dolly, whether used in the conventional dolly manner, that is, in an elevated position above the clothes content

of the tub, or inverted and placed adjacent the bottom thereof, are all of a comparatively expensive construction.

In the present instance, applicant's attention has been turned to the formation of a 55 dolly for washing machines. Well realizing that the tendency in the trade has changed from the wooden type of dolly to one of metal or some substitute material, and especially 60 of late to metal stampings which greatly reduce the cost of production, applicant has devised the present dolly, which is formed of metal, capable of being stamped in a die, the metal itself being either initially rust-proof or capable of being submitted to a rust-proofing process following the completion 65 of the dolly.

In forming the dolly, applicant takes a flat sheet of metal, which when stamped to the shape required for the conventional disk 70 of a dolly, results in the disk portion indicated in Fig. 1 of the drawings as 10. This disk is substantially flat, with the exception of the raised central portion 11 and the curved outer edges 12, which during the stamping 75 operation are curved about a wire 13. This stamping and curving of the outer edge of the disk about the heavy wire 13 is obviously for the purpose of strengthening the disk 80 throughout. It is, of course, plainly to be seen that the metal used is rather thin and for this reason much lighter than a disk that would naturally result from the ordinary casting operation. Also, if the disk were 85 made of wood, it would obviously be considerably thicker.

The initial stamping of the disk 10 also results in the formation of three apertures 14 in the disk, the edges 15 thereof during this operation being left upstanding in a 90 manner to be received by the similarly curved edges of the agitator blades later to be described.

Following the initial formation of the disk 95 with the apertures, the edge portions of which are adapted to receive the blades, the agitator blades 16 are then formed by submitting the thin metal to the operation of a suitable die, whereby the three agitator blades are 100 formed, the shape of same being disclosed

clearly in the various figures of the drawing. It is apparent that these agitator blades conform generally to the blades used upon either metal or wooden dollies, with the outer and water-agitating portions 17 thereof being substantially higher than the inner ends 18. These blades are of substantial thickness, the metal portion thereof being gradually rounded to prevent tearing of the clothes during the 10 agitation of the dolly in the water and against the clothes content.

Following the blanking out of the agitator blades, I find that the edge portions 19 thereof are outwardly curved in a manner to permit 15 engagement thereof with the extended edges 15 of the disk surrounding the apertures 14. Both the disk and the agitator blades are now placed in a suitable die, whereupon a final process results in the clamping of the adjacent 20 edges of the disk and agitator blades in a locked position 20, as clearly shown in the drawings.

This final clamping of the edges of the agitator blades and the disk completes the formation of the dolly, which is now capable of 25 being attached to the driving shaft.

There has been no means shown for connecting the dolly to the drive shaft, whether the shaft be of the type that is projected 30 through the bottom center of the tub or hung from above, it being apparent that any manner of connection with the dolly might well be made.

As respects the operation of the dolly, it is 35 apparent that the same is oscillated within a washing-machine tub in a manner to agitate the water as well as the clothes, with a resulting cleansing of the clothes. The dolly itself, due to the process of forming it, is very 40 light, and for this reason requires a minimum of power in its operation. The dolly also, due to the use of the thin metal, may be formed in such manner that the edges thereof are rounded to prevent damaging contact with 45 the clothes content.

It is apparent that the method of forming the dolly results in a very sturdy construction, as well as one of extremely low cost.

What I claim is:

50 1. The method of forming a metal washing-machine dolly with a wire reinforcement, consisting in first stamping the disk portion thereof with a plurality of apertures therein, slightly flanging the edge portions of said 55 disk apertures and curving the outer edges of the disk about the wire member for the purpose of strengthening the dolly, then stamping a series of smoothly-rounded agitator blades with their edge portions adapted to fit 60 into the said flanged apertures, assembling the said blades with said disk portion, and finally uniting the adjacent flanged edge portions of the disk apertures and agitator blades 65 in a manner to unite the agitator blades with

the disk member as well as to strengthen the entire dolly.

2. The method of forming a metal washing-machine dolly, consisting in first stamping the disk portion thereof with a plurality of flanged apertures therein, then stamping a series of smoothly-rounded hollow agitator blades with their edge portions adapted to fit into the said flanged apertures, said hollow blades deepening toward one end thereof, assembling the said blades with said disk portion with the deeper end of the blades disposed outwardly, and finally uniting the adjacent flanged edge portions of the disk apertures and agitator blades in a manner to unite the agitator blades with the disk member as well as to strengthen the entire dolly.

In testimony whereof I have hereunto affixed my signature.

SIMON E. SCHROEDER.
